MOVABLE WEIR

Hans Zimmermann, Dortmund, Germany, assignor to the firm Vereinigte Stahlwerke Aktiengesellschaft, Dusseldorf, Germany

Application February 10, 1932, Serial No. 592,103
In Germany January 23, 1931

6 Claims. (Cl. 61—28)

This invention relates to movable weirs of the Stoney roller type and more especially to an improved supporting structure of the same both in static and hydraulic respects.

5 Instead of the hitherto used quadrangular cross-section of the weir body with four supporting girders a continuous triangular cross-section with three supporting girders is used according to the invention. The one side of this triangle is 10 in the form of a weir wall which is substantially vertical, while the two main girders form the other sides of the triangle. The main girders have a common longitudinally disposed supporting and connecting beam or flange at their joint 15 and separate beams in the form of flanged sections at the weir wall, the common beam acting for example as a tension beam when arranged at the tail water side of the weir body while the separate beams act as compression beams or 20 flanges. Thereby the favorable mechanical properties of a three beam system are utilized for the weir construction and its resistance against bending and torsional stresses. Furthermore a better water conduct is thereby obtained 25 because the inclined upper girder forms a natural fall so that solid bodies, such as drift-ice or the like, passing together with the water over the weir will not damage it. Finally the jet of water passing under the weir when the latter is 30 raised will not strike the lower main girder or the common beam of the girders so that oscillations of the weir body and damages will not occur.

The invention further relates to an improved 35 construction of the top and bottom edges of the triangular weir body in order to avoid separations of the water jet from these edges and thereby oscillations of the weir body. According to the invention the top and bottom edges of the weir 40 wall are inclined at a definite angle so that they do not meet sharply or they are rounded off. In order to reduce the expenses of manufacture the inclined portions are preferably arranged parallel to the beams of the main girders so that 45 this beam can be constructed normally and a better securing of the weir wall edges to the beam by rivets or like may be obtained.

Another object of the invention is an improved 50 connection of the weir body to the wheel supports at the ends of the same. According to the invention the triangular weir body is connected in its full horizontal breadth to the end plates supporting the bogie wagons without increasing the axle base of the wheels or the breadth of the 55 pier recesses. With such a connection the weir

body gets a greater resistance against torsional stresses especially at its ends, because the weir body is not reduced in width at the ends as in the hitherto used constructions. The novel connection is most advantageous for sluice weirs with 5 large distance of supports.

The invention is illustrated in the accompanying drawings, in which:—

Fig. 1 is a cross-section of the triangular weir body,

Fig. 1a is a plan view according to Fig. 1,

Fig. 2 is a cross-section of the weir body of a submersible sluice weir,

Fig. 3 is a cross-section of the weir body with 10 a damming gate,

Fig. 3a is a plan view according to Fig. 3,

Fig. 4 is a cross-section with a damming or 15 sluice gate and improved stream line with cranked edges of the weir wall,

Fig. 5 is a cross-section of the novel construction of the connection of a triangular weir body with inclined edges to the end plates through line 20 V—V of Fig. 6,

Fig. 6 is a plan of the novel weir body according 25 to Fig. 5 showing the connection with the end plates,

Fig. 7 is a cross-section through the novel weir body through line VII—VII of Fig. 6.

Fig. 1 shows a sluice weir which rests in the 30 damming position on the weir base and can be raised in order to open the passage for the water under the weir. In this figure 1 is the weir wall, 2 the bottom girder and 3 the top main girder of a sluice weir according to the invention. 4 designates the longitudinal supporting beam forming 35 a compression flange for the weir on the head water side, 5 a similar beam for the upper main girder. 6 is the common beam forming a tension flange for the two main girders on the tail water side.

Fig. 2 shows a sluice weir which may be sunk 40 into a recess 23 of the weir base, in a partly sunk position. Owing to the partial lowering of the weir the water passes over the upper edge of the 45 weir and the covering 15 of the top main girder 16 into the tail water. 24 is the jet of the overflowing water.

Fig. 3 shows a sluice weir which at the top is 50 provided with a pivotally mounted weir flap 16 for the conducting of water over the weir which in the damming position rests upon the weir base 55 and which may be raised by means of chains, ropes or the like. The figure shows the weir with lowered flap and partly raised weir body so that 55

the water flows into the tail water both over the flap and under the weir body.

In a weir according to Fig. 1 where water is flowing over the weir only after having stepped over the damming height, the advantage of using the three beam girder consists substantially in the great rigidity of the system towards oscillations and in the high resistance of the system against the hydrodynamic forces of the jet of water passing under the weir when the same is raised, and of the tail water. The superiority of the three beam system according to Fig. 1 over the hitherto used four beam or girder system rests in static respects mainly on the fact that in the three beam girder the compression beams 4 and 5 lie at a distance from each other which is approximately the same as the total height of the weir wall. They therefore increase the amount of inertia of the weir wall which is of decisive importance to the resistance of the system to perpendicular oscillations, much more effectively than the compression beams of the four beam system which lie at a smaller distance. This distance of the main girders of the known construction is namely smaller than two thirds of the height of the weir wall as the water pressure resultant lies from the base at a distance of one third of the weir wall height and as for reasons of construction the bottom main girder has to be raised to a considerable measure above the weir base. The invention thus removes a substantial drawback of the known weirs which frequently leads to stoppages in operation and has prevented the use of such weirs.

However, the invention not only considerably increases the resistance of the supporting structure to the dynamic forces, producing pulsations, of the water jet passing under the weir and of the moved tail water, it also reduces to a minimum the attack of such forces upon the weir system. If the cross-section of the weir is quadrangular, the lower main girder is, when the weir body is partly raised, struck by the water jet which behind the base beam of the weir diverges also towards the top and, in addition thereto, the tension beam of that main girder is affected by the whirl ring formed in the tail water (cf. in this respect the illustration of the water jet and of the whirl ring in Fig. 3). These rhythmically acting forces produce oscillations in the weir body which may become dangerous if the co-efficient of natural oscillation of the weir body coincides with the rhythm of these forces.

If the cross-section is, however, triangular such as appears from Figs. 1, 2 and 3 the water jet passing under the weir no longer strikes the bottom main girder 2, 2' and 2'' owing to the declination of that girder and the tension beam is also withdrawn from the influence of the whirl ring. The invention thus removes for all practical purposes the cause of the well known oscillation phenomenae of weirs with two main girders and at the same time considerably increases the indifference of the supporting system to such influences.

These advantages are, of course, also retained if the three beam system is used for weirs that may be sunk such as for instance are shown in Fig. 2, and for weirs according to Fig. 3 provided with a weir flap.

In the case of sinkable weirs there is the further advantage that the covering necessary to protect the supporting structure and over which the overflow water is discharged into the tail water, is arranged directly on the top main girder 3' or

that the latter itself may be constructed as a water conducting surface. A separate supporting structure such as is necessary in the known construction is thereby made superfluous.

The use of the invention is, as appears, for instance, from Fig. 3, of very particular advantage for weirs with a top flap arrangement. In such weirs the height of the weir wall 1'' is by the overall height of the raised flap lower than the damming height. In consequence the increase of their moment of inertia by the widely spread compression beams of the main girders is particularly valuable. The favorable static effects of the invention are therefore particularly marked in this case of application, the favorable conditions in hydrodynamic respects are fully retained and in addition an ample free space for the exterior support of flap 16 (pipe, flat beam or the like) is produced by the strong declivity of the top main girder 3'' towards the tail water. This free space may therefore be dimensioned without the otherwise necessary limitation by the supporting structure of the weir body. In addition drifts of ice and other solid bodies which slide over the flap in such position in which the flap does not fully cover the weir structure, or in the case when a flap is used which covers only a part of the weir width, slide on the inclined main girder into the tail water without doing damage while they strike with great force upon a horizontally arranged main girder, do damage and cannot be removed unless a separate inclined covering is provided.

The further invention of an improved water conduit in weir bodies by the inclining of the weir edges is illustrated by Fig. 4. In this figure 25 is the perpendicular wall of the sluice weir, 17 the upper and 18 the lower inclined edge of the weir wall, 19 the overflow line adjacent the top inclined edge, 20 the stream line shape of the tightening beam adjacent the bottom inclined edge of the weir wall, 27 the top and 26 the bottom main girder of the three beam system; the beams 29, 22 and 28, 21 respectively, on the head water side, of these main girders which, for example, are shown as angle irons, are rectangularly connected to the inclined weir wall edges 17 and 18 respectively and to the main girders as the latter form with the weir wall edges 17 and 18 an angle of 90°.

Figs. 5 to 7 show the connection of a triangular weir body with inclined edges to the end plates supporting the bogie wagons. In these figures 32 is the top and 31 the bottom main girder with the separate head water beams 34 and 33 resp. and the common tail water beam 35. 30 is the weir wall, 8 the end plate or wheel support which rests with the movable bearings 9 and 10 on the bogie wagons or supporting wheels 11 and 12, and 13 is the pier with its recess 14 in which the weir can be moved up and down.

In the construction shown in Figs. 5 to 7 the tail water beam 35 of the triangular weir body is in a straight line passed through into the area of the end plate 8 and is connected with the same. Towards the tail water the end plate 8 is provided with a somewhat triangularly shaped extension for the connection of the beam which may also be constructed as carrier for the bogie wagons 11, 12 which in a favorable position may be arranged above and beneath the beam without an extension of the length of end plate 8 or a widening of the recess 14 being necessary. The construction of the weir body which is most favorable in static respects and in respect to the

avoidance of weir oscillations, thus is accompanied with the lowest expenditure of weir body and pier building material and nevertheless disadvantages in other respects need not be put up 5 with.

What I claim and desire to secure by Letters Patent of the United States is:

1. A moveable weir of the Stoney roller type comprising a weir body consisting substantially of two main girders and a weir wall and having a continuous triangular cross section, the said main girders and the weir wall representing the sides of the triangle, said body also including two beams for the main girders located adjacent the upper and lower edges of the weir wall and a common beam for connecting the main girders, said beams forming the edges of the triangle. 10
2. Moveable weir of the Stoney roller type including a weir body consisting substantially of two main girders and a weir wall and having a continuous triangular cross section, the top main girder including means acting as a spillway for the overflow water. 15
3. Moveable weir of the Stoney roller type including a weir body consisting substantially of two main girders and a weir wall and having a continuous triangular cross section, the top and bottom edges of the perpendicular weir wall being inclined towards the tail water side of the weir in a straight line so that the level of the said inclined edges come to lie vertically on the level of the adjoining main girders of the weir. 20
4. Moveable weir of the Stoney roller type the body of which has a continuous triangular cross section and consists of a perpendicular weir wall, two convergent main girders which are connected with the weir wall adjacent the upper and lower edges thereof, two separate beams at the connection of the main girders with the weir wall, one common beam at the intersection of the convergent main girders, the said common beam passing in a straight line from end to end of the weir body parallel to the weir wall so that the weir body maintains the horizontal width of its cross section over its entire length, plates at the ends of the weir body and connected with the beams, and bogie wagons connected with the end plates for supporting the weir body, the said 25
5. Moveable weir of the Stoney roller type the body of which has a continuous triangular cross section and consists of a perpendicular weir wall, two convergent main girders which are connected with the weir wall adjacent the upper and lower edges thereof, a covering on the top main girder and acting as a spillway for the overflow water, two separate beams at the connection of the main girders with the weir wall, one common beam at the intersection of the convergent main girders, the said common beam passing in a straight line from end to end of the weir body parallel to the weir wall so that the weir body maintains the horizontal width of its cross section over its entire length, plates at the ends of the weir body and connected with the beams, and bogie wagons connected with the end plates for supporting the weir body, the said bogie wagons being arranged close below and above the connecting point of the said common beam and the end plates. 30
6. Moveable weir of the Stoney roller type the body of which has a continuous triangular cross section and consists of a perpendicular weir wall having inclined upper and lower edges, two convergent main girders which are connected with the inclined upper and lower edges of the weir wall so that their longitudinal axes lie perpendicular to the inclined upper and lower edges of the weir wall, two separate beams at the connection of the main girders with the weir wall, one common beam at the intersection of the convergent main girders, the said common beam passing in a straight line from end to end of the weir body parallel to the weir wall so that the weir body maintains the horizontal width of its cross section over its entire length, plates at the ends of the weir body and connected with the beams, and bogie wagons connected with the end plates for supporting the weir body, the said wagons being arranged close below and above the connecting point of the said common beam and the end plates. 35

HANS ZIMMERMANN.
